ATTORNEY

UNITED STATES PATENT OFFICE.

EDWARD B. JACOBSON, OF PITTSFIELD, MASSACHUSETTS, ASSIGNOR TO J AND B MANUFACTURING COMPANY, OF PITTSFIELD, MASSACHUSETTS, A CORPORATION OF MASSACHUSETTS.

IGNITION-TIMER.

1,325,502.

Specification of Letters Patent. Patented Dec. 16, 1919.

Application filed March 28, 1919. Serial No. 285,742.

To all whom it may concern:

Be it known that I, EDWARD B. JACOBSON, a citizen of the United States, residing at Pittsfield, in the county of Berkshire and State of Massachusetts, have invented certain new and useful Improvements in Ignition-Timers, of which the following is a specification.

The present invention relates to ignition timing apparatus, and more particularly to the contactor carried by the rotary portion. In structural character and operation this invention closely resembles the ignition timing apparatus described in a prior application filed by me November 8, 1918, Serial No. 261,607, and also the invention described in United States Letters Patent issued to me June 27, 1916, No. 1,188,451, for ignition timer; the improvements thereon to which this application relates being confined to the contactor carried by the rotary portion, and involving a substitute structure for the prior corresponding part.

The principal object of the invention is to provide an improved self-lubricating contactor to avoid the usual gumming and poor circuit connections caused by the use of fluid lubricants. A further object is the provision of improved means to prevent arcing of the electric current between the contactor and the several contact elements mounted in the timer casing. A still further object is to provide a contactor which has a rigid setting and an even wiping surface adapted to wear evenly the surface of the several contact elements mounted in the casing, thus avoiding the inequalities of surface wear caused by the use of a movable contactor.

Referring to the accompanying drawing, Figure 1 is a longitudinal vertical section of an ignition timer embodying the present invention in its preferred form and operationally mounted upon a cam-shaft; Fig. 2, a cross section of the same on a line intermediate the rotor portion and the face of the housing; Fig. 3, a longitudinally vertical section of the rotor portion mounted as shown in Fig. 1; Fig. 4, a vertical cross-section of the rotor assembly on a plane coincident with the inner face of the outer radial carrier-arm, the pivotal movement of the contact arm being indicated in dotted lines; Fig. 5, a top view of the con-

tactor carried by the rotor portion; and Fig. 6, a front face view of the same.

The mechanism herein illustrated is designed for use in connection with a four-cylinder explosive engine having a gear-driven cam-shaft operated by the main engine shaft, but it should be understood, however, that my invention is susceptible of application, with slight modification, to motors having any other number of explosion cylinders, and may be otherwise mounted and driven.

This invention may be adapted to any suitable form of housing or casing, the casing 1 herein illustrated being adjustably mounted on the front of the engine housing 2 and arranged to inclose the front end of a cam-shaft 3, which is preferably geared to the main engine shaft (not shown) and extends through a suitable opening in the wall of the engine housing.

The rear end of the casing 1 is open and seated in a circular recess 4 provided on the face of the engine housing 2, said recess being adapted to prevent eccentric displacement of the casing. Forward displacement of the casing is prevented preferably by a spring clamp 5 removably secured at its rear end to a stud or bolt 6 fixed to the wall of the engine housing 2, and engaging at its opposite end the outer extremity of the reduced forward extension of the front of the casing, which has a central depression to receive a boss 7 provided on the clamp 5. Axial movement of the casing for regulating the time of ignition is controlled by a lateral arm 8 exteriorly mounted on the casing and provided with a bearing 9 to receive a control-rod (not shown.)

Within the casing 1 is an insulation ring 10 provided at regular intervals with arcuate contacts 11, 11, which are embedded on its inner rim and suitably connected to separate terminals 12, 12, etc., arranged on the outside of the casing 1, for connection with the primary circuit of separate induction coils.

Mounted to rotate with the shaft 3 within the casing 1 is a metallic carrier 13 in the form of a sleeve which is normally secured against axial movement on the shaft by a transversely arranged removable pin 14 projecting through a suitable opening in the shaft and extending at one of its ends into

a slot 15 provided on the outer rim of the carrier. The pin 14 is secured against end-wise displacement by a cup washer 16 fitted over the outer end of the carrier and in closing the exposed end of the pin 14, the reduced outer end 17 of the shaft being projected through the cup washer 16 and suitably threaded to receive a pair of nuts 18, 19, which are employed in conjunction with 10 a flat washer 20, carried on the reduced end of the shaft and engaging the face of the cup washer, to secure the latter in position. The carrier 13 is laterally provided with a pair of fixed radial arms 21, 21, arranged 15 in spaced parallel relation to each other and pivotally supporting at their outer ends a contact-arm comprising a pair of oppositely arranged plates 22, 22, which are curved in outline and are secured at their rear ends 20 to the carrier arms by a transversely arranged pin 23. Said pin 23 has reduced extensions 24, 24, at opposite ends adapted to fit into corresponding openings provided in the plates 22, 22, and are slightly burred 25 at their extremities to prevent lateral displacement of the plates. The contact-arm is reinforced centrally by a transverse spacer-pin 25, which is similar in form and manner of attachment to the pin 23, and is 30 adapted to maintain the relative spacing of the plates 22, 22.

Mounted between the front ends of the plates 22, 22, and secured thereto in manner similar to the pins 23, 25, is a separate contact-supporting pin 26, preferably of uniform diameter and adapted to extend through a corresponding opening provided in the base of the contactor 27 which has a solid body structure of substantially square 40 formation in cross-section and is rigidly seated in the jaw formed by the plates 22, 22. The side faces of the contactor 27 are cut away at 28, 28, to seat the outer extremities of the plates 22, 22, which are also preferably cut away on their upper margins to provide even supporting edges.

The outer or top face of the contactor 27 is arcuate in outline to conform to the curved surface of the insulation ring 10 which it 50 normally engages by an even sliding contact, proper lubrication of the opposing faces of these parts being supplied from a centrally arranged transverse slot 29 provided in the top face of the contactor and 55 extending inward to a middle point of its length, and adapted to receive a preferred form of solid lubricant, such as a composition of graphite and tallow which is released gradually and proportionately to the wear 60 of the surface of the contactor, thus avoiding unnecessary gumming of the surface. Arcing of the electric current at the instant of opening or closing the circuit accordingly as the contactor reaches or leaves the 65 several contact-elements is prevented by the

provision of facings of suitable insulation such as the fiber strips 30, 30, seated in suitable slotted recesses on the front and rear faces of the contactor 27.

The free end of the contact-arm is impelled outward and maintained normally in engagement with the insulation ring 10 through the medium of the contactor under the impulse of a torsion spring 31 which is constructed, arranged and operated in the 75 manner shown and described in my said prior Letters Patent, while the outward swing of the contact-arm assembly is limited by the provision of positive stops 32, 32, also 80 constructed and arranged as shown and described in the aforesaid Letters Patent, reference to which is herein made for further particulars.

I claim:

1. In an ignition timer, the combination 85 with a casing and contact-elements mounted in the casing, of a rotary portion mounted to move in the casing and comprising a carrier, an arm pivotally secured to the carrier and having a free end terminating in 90 a jaw adapted to be swung toward and away from the contact-elements, a stationary contactor having a body-portion seated at its inner end in said jaw and extending at its outer end laterally away from the contact-arm, said outer end having a bearing-face 95 adapted to establish a wiping contact successively with the contact-elements in the casing and having an opening therein for carrying a lubricant for distribution on the 100 contact-elements.

2. In an ignition timer, the combination with a casing and contact-elements mounted in the casing, of a rotary portion mounted to move in the casing and comprising a carrier, an arm pivotally secured to the carrier and having a free end terminating in a jaw 105 adapted to be swung toward and away from the contact-elements, a stationary contactor having a body-portion seated in said jaw 110 and extending laterally away from the contact-arm and terminating at its outer end in a bearing-face adapted to establish a wiping contact successively with the contact-elements in the casing, and means provided 115 on the contactor for preventing arcing of the electric current between the contactor and the contact-elements.

3. In an ignition timer, the combination with a casing and contact-elements mounted in the casing, of a rotary portion mounted to move in the casing and comprising a carrier, an arm pivotally secured to the carrier and having a free end terminating in a jaw 120 adapted to be swung toward and away from the contact-elements, a stationary contactor having a contact block rigidly seated in said jaw and extending toward the contact-elements and terminating at its outer end in a curved contact face conformed to the facial 125 130

arc of each of the contact-elements and having a centrally arranged transverse slot therein to receive a lubricating substance for distribution successively on the contact-elements.

4. In an ignition timer, the combination with a casing and contact-elements mounted in the casing, of a rotary portion mounted to move in the casing and comprising a carrier, an arm pivotally secured to the carrier and having a free end terminating in a jaw adapted to be swung toward and away from the contact-elements, a stationary metallic contact member seated in said jaw and ex-

tending toward the contact-elements and terminating at its outer end in a curved contact face corresponding in outline to the facial arc of the contact-elements, and insulation members secured to the front and rear edges of the contact member and forming portions of the contact face.

In testimony whereof I hereunto affix my signature in the presence of two witnesses.

EDWARD B. JACOBSON.
